UNITED STATES PATENT OFFICE.

EMANUEL GROSSMAN, OF BROOKLYN, AND PASQUALE MALAGRINO, OF NEW YORK, N. Y.

SHOE.

1,256,476.

Specification of Letters Patent. Patented Feb. 12, 1918.

Application filed October 4, 1913. Serial No. 793,498.

To all whom it may concern:

Be it known that we, EMANUEL GROSSMAN and PASQUALE MALAGRINO, citizens of the United States, and residents of Brooklyn, in 5 the county of Kings, and New York, in the county of New York, respectively, and State of New York, have invented certain new and useful Improvements in Shoes, of which the following is a specification.

10 This invention relates to boots and shoes, and more particularly to means for fastening heels to boots and shoes.

An object of this invention is to provide improved means for positively holding heels 15 to shoes or the like to prevent accidental separation by shock, torsion or other means which would pry a heel loose.

Further objects of this invention will be disclosed from the following specification, 20 claim, and the drawings in which,

Figure 1 is a side elevation of a shoe with parts in section, showing one form of fastening means,

Fig. 2 is a similar view showing another 25 form of fastening means,

Fig. 3 is a bottom view of a shoe with the heel removed, showing the plate carried by the rear of the sole,

Fig. 4 is a similar view showing a modification of the plate used, and

Fig. 5 is a cross sectional view through the portions of a shoe and heel adjacent to the fastening means.

Referring to the drawings, there is shown 35 a shoe 10 to which is secured a heel 11. This heel may be secured by shoe pegs and cement usually employed for fastening heels to shoes, but to insure a strong and substantially secure fastening, the sole of the shoe 40 at the rear is provided with a plate 12 which is stamped so as to have an elevated slot 13 cut into it. This plate may be secured to the sole of the shoe by means of nails or other fastening means 14, passing through said 45 plate, sole, and inner sole, when the ends of said nails may be clenched as shown.

The heel 11 may have screws 15, as shown in Fig. 1, or nails 16, as shown in Fig. 2, se-

cured in the upper concaved surface thereof, and these screws or nails have their heads 50 disposed to be slid in the slot 13 of the plate 12. It is apparent that the heads of these screws or nails, as the case may be, and the plate 12 provide a positive locking means for the heel, and shoe, but to hold the heel 55 against displacement by longitudinal movement, the heel is further secured by shoe pegs, or nails 19, and by cementing the contiguous faces of the heel and shoe or by other known means.

It may be desired to reverse the relative positions of the screws or nails, in which case the plate is fastened to the heel and the nail or screw is fastened to the rear of the sole, and the result as to strength and security 60 of fastening will be the same.

Fig. 4 shows a slight modification, in which a plate 17 has a key-hole slot stamped therein, and in which slot, the heads of the screws or other fastening means are passed 70 and slid to cause the enlarged heads to engage the edges of the constricted portion of the slot. When this plate is used there is space provided for the sliding head either by making a slight cavity in the leather 75 upon which the plate rests or in the plate itself.

Further modifications may be made within the scope of the appended claim without departing from the spirit of this invention.

What we claim as new is:

In a shoe, a heel provided on its seat with one member of detachable fastening means, another member of such fastening means secured to the heel seat of the shoe, and a plurality of nails permanently securing the sole 85 of the shoe to the heel and located around the edge of the heel seat.

Signed at Brooklyn in the county of Kings and State of N. Y. this 29th day of Sept. 90 A. D. 1913.

EMANUEL GROSSMAN.
PASQUALE MALAGRINO.
